AIR DISTRIBUTOR

Jerold H. Van Alsburg and William C. De Roo,
Holland, Mich., assignors to Hart & Cooley
Manufacturing Company, Holland, Mich., a
corporation of Delaware

Application June 17, 1946, Serial No. 677,202

2 Claims. (Cl. 98—40)

1

The present invention is directed to distribution of air and in practical use, as disclosed, is used at the outlet end of an air carrying conduit or pipe through which the air is circulated and by means of our invention, the air may be laterally directed and distributed in varying amounts in the different directions which it may go.

It is an object and purpose of the present invention to provide an air distributor for the purpose stated which is of an economical construction, readily and easily applied or installed, and very simply and easily adjusted for varying the quantity of air distributed in selected directions of movement thereof and which, as to its outer appearance when in use, is of an attractive form and is not unsightly, but adds to the appearance of a room in which it is located.

An understanding of the invention may be had from the following description taken in connection with the accompanying drawings in which,

Fig. 1 is a vertical section substantially on the plane of the line 1—1 of Fig. 2.

Fig. 2 is a horizontal section through the air distributor as it is installed at the inner side of a wall of a room.

Fig. 3 is a fragmentary somewhat enlarged horizontal section of the central portion of the distributor.

Fig. 4 is a view similar to Fig. 2 of a modified form of structure.

Fig. 5 is a vertical section substantially on the plane of line 5—5 of Fig. 4.

Fig. 6 is a fragmentary horizontal section, similar to Fig. 3, of the modified form of construction.

Fig. 7 is a perspective view of one of a plurality of sections used in the modified form of structure to make the inner conical and fluted air directing cone thereof.

Fig. 8 is a vertical section substantially on the plane of line 8—8 of Fig. 9 of a further form of the invention and,

Fig. 9 is a transverse section substantially on the plane of line 9—9 of Fig. 8.

All of the sectional views are taken in the directions indicated by the arrows, and like reference characters refer to like parts in the several figures of the drawings.

The air distributor of our invention is installed at the inner side of the wall of a room over the outer end of an air carrying flue or conduit. Portions of the wall, such as the lath at 1 and plaster at 2, are shown in the drawings and at an opening therein over which the air distributor is located, a ring or frame member 3 of sheet metal

is positioned having a wall extending into the opening, which is turned outwardly so that its outer side is substantially flush with the inner plaster side 2 of the room wall, and is then bent into an angular form as indicated at 4, the terminal flange or leg of which is covered by the plaster. The delivery end of the air flue or conduit 5 is surrounded by the ring or frame 3. Air is moved or circulated or forced in an outward direction through the flue 5, as indicated by the arrows in Fig. 2, and if nothing more in the way of structure was used, would move directly in line with the axis of the flue 5 horizontally outward as a solid current of air.

15 The air distributor of our invention includes a base plate 6 of thin sheet metal, at its edges provided with a bead 7 concaved at its outer side. Plate 6 has a central opening preferably larger than the cross sectional area of the flue 5. Said plate 6 lies against the ring member 3 and is secured thereto by screws, as shown. An outer plate 8 also of sheet metal is connected with the bead 7 by means of a plurality of yielding or spring fingers 9, which may be inserted through 20 slots at the inner sides of the beads, as many as necessary, the edges of the plate 8 being spaced a short distance from the inner sides of the bead 7. Thus there is a continuous relatively narrow space all around the plate 8 for the outward passage of air. The plate 8 is provided with a central opening 10, which may be of a circular form which is covered by a plate 11, of a materially larger diameter than the diameter of the opening 10. The base plate 6 and the plate 8, shown as 25 of generally rectangular form with rounded corners, may, of course, be varied in outline. Likewise the flue 5, indicated in Fig. 1 as of a rectangular outline, may also be differently shaped with departing from the invention.

30 At the inner side of the outer plate 8, a conical and radially fluted air directing member 12 is located, the central conical portion of which projects toward the delivery end of the flue 5. From the apex of the cone outwardly, a plurality of spaced outwardly pressed ribs or flutes 13 extend as shown in Fig. 1. In the construction, shown in Fig. 1, also in Fig. 8, the flutes are generally radially disposed and progressively increase in height from the apex of the cone outwardly nearly to their outer ends, and are spaced approximately equal distances from each other. They vary in length, the diagonally disposed flutes being longer than the others and the vertically disposed flutes somewhat shorter than 35 those horizontally located. This provides a series 40

50 55

of channels between the flutes whereby when air is forced in an outward direction from the flue 5, it is directed outwardly and laterally by the curved bottoms of the channels between the flutes and passes out at the narrow slot-like openings between the edges of the plate 8 and inner sides of the beads 7.

Such air directing member, as shown in Fig. 3, is yieldingly held against the inner side of the plate 8 by a coiled tension spring 14, connected at one end to a threaded stem 15 having a nut screwed on its outer portion which passes centrally through the circular plate 11 and at its other end to a bridge 16 secured within the apex of the cone.

When the cone apex is at the geometric center of the flue 5, the air is equally distributed through the narrow outlet openings around the edges of the plate 8. It is evident that the inner fluted cone member has a range of adjustment, limited by the size of the opening 10, and that the cone member 12 may be shifted over the inner side of the plate 8 to a large number of different positions and will be yieldingly retained in any position to which moved by the tension spring 14. The conical member 12 and the plate 11 in such change of position are moved together relative to the fixed plate 8, with opening 10 always closed by plate 11. Therefore, as shown in Figs. 1 and 2, a greater amount of air is directed to the left as the apex of the cone is a limited distance to the right of the central axes of the flue 5, whereby a larger amount of air coming from the flue 5 is directed against the left hand portion of the fluted conical surface. By shifting the conical member to different of the indefinite number of positions to which it may be moved, the quantity of air passing from the air distributor may be widely varied as to the amounts that flow in different directions.

In Figs. 4 to 6 inclusive, the structure is identical except with respect to the inner fluted conical air distributor member. Instead of being made from a single plate of sheet metal 12, it is made of a plurality of sections 17, each substantially a conical sector, which at its apex end is formed with a horizontal ear 18 having a central opening through and with a flute 13a at one edge. In the construction shown in Figs. 4 to 7, the air carrying flue is of circular form and the co-operating parts of the structure have circular outlines to correspond. The various sectors may be disposed with the ears 18 in superimposed relation (Fig. 6) and with side edges overlapping. A bolt 19 passes through the openings in all of the superimposed ears 18 for connecting them together and to the inner end of the bolt, a tension spring 20 is connected at one end, the other end having connection to a headed pin 21 passing centrally through the plate 11, serving the same purpose as the spring 14 in the previously described structure.

With the structure shown in Figs. 4 to 7 inclusive, the several sectors may be adjusted with respect to each other varying the positions of the flutes 13a as to spacing with a corresponding variation in the passage of air. And, of course,

the fluted conical composite structure made up of all of the sectors connected together is changeable as to position, the same as in the previously described structure within the limits described by the opening 10.

In Figs. 8 and 9, the structure is substantially identical with that shown in Figs. 1 and 2, except that the fluted conical inner plate 12 is fixed in position and is not adjustable over the inner side of the plate 8. This permits an elimination of the retaining clips 9, plate 11 and spring 14, the outer plate 8 and the conical fluted plate 12, also the plate 6, being all secured in place by a plurality of screws 22 having spacing sleeves 23 around them between the wall plate 6 and the conical plate 12. With such construction a variation in the distribution of the air through the outlet slots between the edges of the outer plate 8 and the bead 7 is not obtained, but there will be a substantially equal distribution all around the plate 8.

The construction described is one readily and easily manufactured from thin or light sheet metal, the assembly is readily made and installation is simple and easy.

The invention is defined in the appended claims and is to be considered comprehensive of all forms of structure coming within their scope.

We claim:

1. An air distributor comprising an air conduit having an outlet opening, a plate larger than said outlet opening and spaced therefrom providing an air passage substantially around its entire periphery, a substantially conical deflector being located against said plate and adjustable thereon laterally of said opening and the apex of the deflector extending toward said outlet opening means for fastening said deflector to said plate in adjusted position, said conical deflector being composed of a series of segments adjustable relative to each other about said apex and an upstanding rib on each segment extending radially of said apex.

2. The elements of claim 1 in which said segments are of sheet material overlapping each other and the dimension of the arc of the periphery of each segment is greater than the ratio of the number of segments to the entire circumference of the base of the deflector.
